UNITED STATES PATENT OFFICE.

CHARLES F. ROPER, OF HOPEDALE, MASSACHUSETTS, ASSIGNOR TO
DRAPER COMPANY, OF HOPEDALE, MASSACHUSETTS, A CORPO-
RATION OF MAINE.

GRINDING-MACHINE.

SPECIFICATION forming part of Letters Patent No. 714,036, dated November 18, 1902.

Application filed June 19, 1902. Serial No. 112,315. (No model.)

To all whom it may concern:

Be it known that I, CHARLES F. ROPER, a citizen of the United States, and a resident of Hopedale, county of Worcester, State of Massachusetts, have invented an Improvement in Grinding-Machines, of which the following description, in connection with the accompanying drawings, is a specification, like characters on the drawings representing like parts.

10 This invention relates to grinding-machines adapted to grind the cylindrical end or ends of an article to a conical or tapered shape, and in the present embodiment of my invention I have shown a machine particularly adapted for grinding the ends of a spinning spindle-blade.

It is customary to point the ends of the spindle-blade, the tip thereof being permitted to retain its conical shape; but the opposite 20 end of the blade is usually flattened after pointing to present a frusto-conical shape, such end being supported by a suitable step when the spindle is in use. Such pointing of the ends of the spindle-blade has heretofore 25 been accomplished by hollow mills; but certain objections pertain to such practice, and I have invented a grinding-machine for shaping or pointing the ends of the spindle-blade by grinding, and in the machine to be hereinafter described the movement of the blank 30 during the grinding is automatically controlled, so that as the grinding progresses the desired taper is effected. I have also in the present embodiment of my invention provided for simultaneously grinding the opposite ends of the blank, (generically designated the "work,") and when a predetermined 35 grinding has been effected the work is automatically moved out of the field of action of the grinding-surface.

As will appear fully hereinafter, the insertion of the work into the work-holder and the movement of the latter to present the work to the grinder are the only manual operations 40 in the process until the grinding is completed, the work-holder automatically returning thereafter into position for the finished work to be removed and a new piece to be inserted.

50 Various adjustments are provided to ac-

commodate the machine to spindle-blades of different sizes and means are provided for automatically equalizing the wear upon the grinding-surfaces.

These and other novel features of my invention will be hereinafter described in the subjoined specification, and particularly pointed out in the following claims.

Figure 1 is a top or plan view of a grinding-machine embodying one form of my invention, the work-holder being shown in position to receive the work. Fig. 2 is a front elevation thereof. Fig. 3 is a right-hand end elevation of the machine illustrated in Figs. 1 and 2, the power-transmitting belts being omitted for the sake of clearness of illustration. Fig. 4 is a longitudinal vertical section of the work-holder, taken on the line $x-x$, Fig. 1, the work being indicated by dotted lines. Fig. 5 is an enlarged detail, in plan and partly broken out, of the device for effecting the opening of the clamping means of the work-holder. Fig. 6 is a longitudinal sectional detail on the line $x'-x'$, Fig. 1, of one of the grinders and the supporting means therefor. Fig. 7 is an enlarged front elevation of the means for automatically controlling the bodily movement of the work-holder, the movable pattern and the actuating mechanism therefor being clearly shown. Fig. 8 is a sectional view thereof on the line x^2-x^2 , Fig. 7, looking toward the left. Fig. 9 is a side elevation of a spindle-blank ready to be ground at its ends, and Fig. 10 is a similar view of the blank after its ends have been pointed by grinding 85 by the machine herein illustrated. Figs. 11 and 12 are enlarged sectional details of one of the chuck-bodies and its corresponding collet or work-clamp, respectively.

The frame of the machine is of suitable 90 shape and size to properly support the operating parts and comprises, essentially, a heavy bed A, having a central longitudinally-extended and raised portion A', on which the work-holder is mounted, and oppositely extended, but non-aligned parallel wings A² A³. At its rear end the bed has erected upon it two like standards A⁴, provided with bearings for a shaft B, provided with a pulley B', adapted to be driven from any suitable 100

source of power by a belt, (not shown,) said shaft having fast upon it two like eccentrics $B^2 B^3$, provided, respectively, with straps $b^2 b^3$, said shaft being shown in Fig. 1 as parallel to the wings $A^2 A^3$, the eccentrics being mounted on the shaft outside the standards and near its ends. The said wings are of like construction and each one supports a grinder, and inasmuch as the latter and their supports are alike it will only be necessary to describe in detail one of said wings and the parts mounted thereupon, the two grinders, however, being indicated by the letters $G^2 G^3$ for convenience. Each wing has on its top two parallel undercut ribs a , extending the length thereof and forming a guideway or track for a cradle C , its foot resting on and being slidable upon the top of the wing and having a longitudinal mortise c^x to embrace the ribs a . (See dotted lines, Fig. 3.) The ends of the cradle are upturned at c to form bearings for a fulcrum shaft or pin C^x , which is extended through a hole in the lower end of a rocking head C' , inserted between the ends c of the cradle and made rigid with the fulcrum member by a set-screw c' , Fig. 2. A washer c^2 , surrounding the reduced outer end c^3 of the fulcrum member, is held against the outer face of the adjacent upturned end c of the cradle by check-nuts c^4 , screwed upon the reduced end, which is threaded, so that wear can be compensated for between the contracting portions of the cradle and head. A bracket c^5 , secured to the outer end of the wing, is upturned to provide a bearing c^6 , Fig. 6, for an adjusting-screw c^7 , a collar c^8 and head c^9 , fast thereon on opposite sides of the bearing, preventing longitudinal movement of the screw, the inner end of which extends between the ribs a and engages a threaded nut c^{10} , secured to the bottom of the cradle and depending between the ribs. By rotating the screw the cradle and the parts supported thereon can be moved in or out longitudinally of the wing to move the grinding-surfaces toward or from each other, according to the length of the work and the angle to be ground.

Referring more particularly now to Fig. 6, each of the rocking heads C' is upturned at its ends, as at $c^{12} c^{13}$, to receive journal-boxes $C^{12} C^{13}$, respectively held in place by suitable caps 12 and 13, and in these boxes the grinder-shaft is rotatably mounted. This grinder-shaft G is provided at its end nearest the grinder with two annular enlarged shoulders 15 and 16 to coöperate with corresponding annular recesses in the adjacent end of the journal-box C^{13} , and said shaft is reduced in thickness at g to leave an annular shoulder 17, and a pulley G^x is splined onto the shaft and butted against the shoulder 17, the hub of the pulley at the end adjacent the journal-box C^{13} being shouldered, as shown in Fig. 6, to correspond with the recessed end of the journal-box. Beyond the pulley the shaft G is provided with annular shoulders 18 and 19

to coöperate with corresponding recesses in the inner end of the journal-box C^{12} , the reduced part g' of the shaft rotating in the journal-box. An annular collar g^2 is screwed onto the extremity of the part g' of the grinder-shaft, which is threaded for the purpose, and check-nuts g^3 hold said collar in place against the outer end of the journal-box C^{12} .

The arrangement of parts is such that the entrance of grit or dust and dirt into the bearing for the grinder-shaft is made very difficult and practically prevented, so that the wear is reduced to a minimum. It is necessary to protect the bearings of the grinder-shaft, inasmuch as they are so close to the grinding-surface.

Each grinder is shaped, as shown in Figs. 3 and 6, to present an annular flat grinding-surface g^x , and the grinder is secured to the shaft by a screw-stud g^4 , which is screwed into the larger end of the grinder-shaft, passing through a central hole in the grinder, and a washer g^5 is interposed between the bottom of the circular recess g^6 in the grinder and a check-nut g^7 , which is screwed onto the threaded outer end of the screw-stud g^4 . The grinder is thus rigidly secured to the grinder-shaft, but can be readily removed therefrom when worn or otherwise and a new grinder substituted.

Referring to Figs. 1 and 2, it will be seen that the grinding-surfaces of the two grinders $G^2 G^3$ are located in parallel planes and that the axes of rotation of the two grinders are in parallelism, but non-alined. The rocking head C' , which is mounted on the wing A^2 , has one of its upturned portions c^{13} provided with ears c^{33} , between which is pivotally connected by a stud b^8 a link b^9 , the free end thereof being adjustably connected by a turnbuckle b^{10} with the arm b^{20} of the eccentric-strap b^2 , so that by means of the eccentric B^2 the grinder G^2 will be reciprocated by or through the rotation of the shaft B . The upturned portion c^{13} of the rocking head C' , which is mounted on the wing A^3 , is provided with ears c^{34} (see Fig. 1) to receive between them a link b^{19} , pivotally connected with the ears by a stud b^{18} and adjustably connected by a turnbuckle b^{100} with an arm b^{30} , secured to and forming a part of the eccentric-strap b^3 . The turnbuckles $b^{10} b^{100}$ are alike, and so, too, are the eccentric-straps and the eccentrics $B^2 B^3$; but owing to the nearness of the wing A^3 to the shaft B the link b^{19} is much shorter than the link b^9 , connected with the other grinder.

By the connections described the grinders are continuously reciprocated during the operation of the machine, while their grinding-surfaces are maintained in parallel vertical planes.

By means of the turnbuckles the paths of movement of the grinders can be adjusted or changed to accommodate the work, the reciprocation of the grinding-surface while the

grinder is rotated serving to equalize the wear upon the acting or grinding surface, and thereby prevents scoring or ridging thereof. If the grinders are bodily adjusted in or out 5 on the supporting-wings of the frame, the eccentricities B^2 B^3 will be correspondingly adjusted on the actuating-shaft B.

The raised and longitudinally-extended central portion A' of the bed has mounted 10 upon it the work-holder, which is adapted to swing bodily on a vertical fulcrum or pivot between the grinding-surfaces to present the ends of the work simultaneously to the latter or to withdraw them therefrom, and, as 15 will hereinafter appear, means are provided for automatically clamping the work in the work-holder by or through its movement from normal or work receiving and discharging position into position to present the work to 20 the grinding-surfaces and to effect automatically the unclamping of the work when the work-holder is swung back into work receiving or discharging position.

Referring more particularly to the vertical 25 longitudinal sectional view of the work-holder in Fig. 4, a turn-table W, having a longitudinally-extended top W^x rigidly secured thereto, is pivotally connected by a vertical turret-bolt W' with the part A' of the bed, 30 the turn-table being recessed to receive the head w' of the turret-bolt, which latter is shouldered at w and threaded at its lower end to receive set-nuts w^2 , which act upon a washer w^x , the turret-bolt being thereby 35 clamped to the top of the part A'. The head W^x of the turn-table is provided with parallel longitudinal undercut guideways w^3 , (see Figs. 1, 2, and 4,) said guideways being interrupted midway between their ends to receive 40 between them a transverse block w^4 , having a recess in its top for a purpose to be described, the block w^4 being secured to the head of the turn-table by suitable screws, as 6. Upright chuck-brackets W^2 are mounted 45 to slide on the guideways w^3 , and by referring to Fig. 4 it will be seen that these chuck-brackets are alike in their general shape and construction, the foot of each bracket being mortised to embrace the guideways, and a 50 right and left hand threaded adjusting-screw w^5 engages threaded nuts w^6 , secured to the foot of each bracket and depending between the guideways w^3 . The adjusting-screw is provided with fixed collars w^7 on each side 55 of the transverse block w^4 , the recess in the top of the latter serving as a seat for the cylindrical part of the adjusting-screw between the two collars, the block co-operating with the collars to prevent longitudinal movement 60 of the screw. By rotating the latter in one direction or the other the chuck-brackets W^2 will be moved toward or from each other to adjust the work-holder to the length of the work, and I have herein shown the adjusting-screw as nicked at its ends, as at w^8 , whereby 65 by means of a screw-driver the screw may be rotated to effect the desired adjustment of

the chuck-brackets. Each chuck-bracket at its upper end is provided with a bearing w^9 for the body of the chuck to be described, a 70 cap w^{10} completing the bearing or seat for the said chuck-body, the longitudinal axes of the two chuck-bodies being in alinement and in a longitudinal plane intersecting the longitudinal center of the turret-bolt W' . Each 75 chuck-body comprises a sleeve w^{12} , Figs. 4 and 11, having at its inner end a broad annular flange w^{13} and near its outer end a narrower annular flange w^{14} , and between the flanges a bushing of bronze or other suitable 80 metal w^{15} surrounds the chuck-body interposed between it and the bearing and cap of each chuck-bracket. An annularly-grooved pulley w^{16} is rigidly secured upon the inner flange w^{13} to rotate therewith, and beyond 85 the outer flange w^{14} the chuck-body is extended, as at w^{17} , to receive a chuck-cap w^{18} , rigidly secured in any suitable manner thereto. Longitudinal movement of the chuck in the bracket W^2 is prevented by means of the pulley w^{16} and the inner end of the chuck-cap w^{18} , as will be manifest by an inspection of 90 Fig. 4. A collet or work-clamp w^{19} is mounted in each chuck-body, the collet or clamp being shaped interiorly to accommodate the 95 work, in this instance a spindle blade or blank, and it is longitudinally split, so that when the clamp or collet is moved outward the elasticity of the metal thereof will cause it to spring out or open to release or unclamp 100 the work. Each collet or clamp at its inner end has rigidly secured to it a sleeve w^{20} , (see Fig. 12,) concentric therewith and extending into the interior of the chuck-body w^{12} , which latter is of sufficiently large internal diameter 105 to receive a strong coiled spring s surrounding the collet, the outer end of the spring bearing against an internal shoulder w^{21} , formed on the chuck-body, the opposite end of the spring bearing against the inner end 110 of the sleeve w^{20} and normally tending to retract the collet or clamp w^{19} into the position 115 shown in Fig. 4 to contract the same and clamp the work. Manifestly if the collets or clamps are moved outwardly in opposition to 120 the stress of their springs s the resiliency of the metal of which the clamps are composed will operate to open them to release the work. Each chuck-bracket W^2 has secured to it on 125 its inner upright side an ear w^{22} , on which is fulcrumed at w^{23} an upright lever w^{24} , having its upper end bifurcated or forked, as at w^{25} , to straddle or loosely surround the work when the latter is in position, the bifurcated part of the lever bearing against the inner 130 end of the adjacent collet or clamp, and the lower or depending end of each lever engages the inner headed end of a plunger w^{26} , mounted to slide longitudinally in the lower part of each chuck-bracket, the outer ends of the two plungers projecting beyond the brackets, as clearly shown in Fig. 4. I have provided means for automatically engaging and pushing the plungers w^{26} inward when the work- 135

holder is bodily swung upon its fulcrum W' into position to receive or discharge the work, and an enlarged detail in plan of one of these devices is shown in Fig. 5. An upright post 5 D is rigidly secured to the part A' of the bed at each end thereof, and upon the top of each of these stands is pivotally mounted at d^x a horizontally-swinging arm d , the free end of each arm having pivotally connected to it at 10 d' a short arm d^2 , cut away at its inner end at d^3 to leave a projecting end or shoulder d^4 , and a spring s^x (see Fig. 5) is interposed between the pivoted end of the short arm d^2 and a socket in the arm d' , the spring acting to 15 normally swing the short arm into the position shown in Fig. 5. The short arms d^2 are located in the horizontal paths of movement of the outer ends of the plungers w^{26} , one arm for and to coöperate at times with each plunger, and an adjustable stop-screw d^5 is horizontally mounted in an upturned standard D^X , forming a part of the bracket or casting D^2 , which carries the post D and so located that the inner end of the stop-screw will be 20 behind and closely adjacent the pivoted end of the short arm d^2 . (See Fig. 3.) Now when the work-holder is swung from its operative position, which is at an angle to the position shown in Fig. 1, toward the position shown 25 in Fig. 1 the projecting ends w^{26} of the plungers will be moved into engagement with the cut-away ends d^3 of the two short arms d^2 , and the latter will be swung on their fulcra d' against the stress of their springs s^x as the 30 work-holder approaches the position shown in Fig. 1, the stop-screws d^5 preventing any swinging movement of the arms d , and when the work-holder assumes the position shown in Fig. 1 the arms d^2 will be substantially in 35 alignment with the two plungers w^{26} , and by such movement of the arms d^2 from the position shown in Fig. 5 they will act with the plungers as a species of toggle-joint and will gradually force the plungers inward, to there- 40 by rock the upturned levers w^{24} on their fulcra and move the collets or work-clamps w^{19} outwardly relatively to the chuck-bodies to release or unclamp the work, and the completed work can then be removed from the chucks and 45 50 another piece of work inserted. Supposing a blank, such as shown in Fig. 9, having been inserted in the work-holder, such insertion being effected by pushing it longitudinally through the open clamps rearwardly until the 55 inner end of the blank engages a stop-gage, to be described, so that the blank will assume the dotted-line position shown in Fig. 4, the operator by means to be described swings the work-holder bodily to present the work to the 60 grinding-surfaces, and as the work-holder is thus swung the plungers w^{26} pass from engagement with the arms d^2 of the releasing devices, hereinbefore described, and the strong springs s , Fig. 4, immediately operate 65 to retract the collets or clamps into the chuck-bodies and firmly clamp the work in the chucks to be rotated bodily therewith, the

clamping of the work being effected before the work is presented to the grinding-surfaces $G^2 G^3$. The head W^x is secured by bolts 8, 70 Fig. 1, to the turn-table, and the latter has rigidly secured to it a handle W^8 , which is moved in the direction of the arrow 10 by the operator to swing the work-holder to present the work to the grinding-surfaces, such swinging movement of the work-holder being resisted by a strong spring S, attached at one end to the base of the handle and at its other end to a fixed pin 100. (See Fig. 1.) A size-gage H is adjustably secured by a set-screw 80 h to the top of the part D^x of the front bracket D^2 in the horizontal path of movement of the outer end of the work when the work-holder is swung to prevent such swinging movement if a blank of improper length is inserted in 85 the work-holder, and on the part D^x of the rear bracket D^2 a stop-gage H^x is adjustably mounted by means of a set-screw h^x and in the path of movement of the inner or rear end of the work when inserted in the work- 90 holder. This stop-gage indicates to the operator when the blank or spindle-blade is properly positioned in the work-holder, the acting end of the gage being concaved, as at h^2 , on a circle having as its center the center of the 95 turret-bolt W' .

Referring to Fig. 1, it will be noticed that the size-gage H is offset from the longitudinal center of the chucks when the work-holder is in position to receive or discharge the work 100 in order to permit the operator to handle the work, and the acting end of the gage is also concave, as at h^3 , to permit the outer end of the work to swing clear of the same when the work-holder is swung. 105

When the work has been presented to the grinding-surfaces by the described manual movement of the work-holder, the grinding operation begins, and as the work is ground away the work-holder must be moved to keep 110 the work up to the grinding-surface until the desired shape or taper of the ends of the work has been attained, and I have herein devised means for automatically controlling the 115 swinging movement of the work-holder for this purpose, the construction being such that the movement of the work-holder to operatively position the work enables the automatic means to automatically assume control of the work-holder. 120

As will appear hereinafter, when the grinding has been completed—that is, when the predetermined taper has been imparted to the ends of the work—the work-holder is automatically released from the automatic controlling means, and such work-holder is 125 swung back to receiving or discharging position (shown in Fig. 1) by or through the action of the strong spring S.

Referring to Figs. 1, 3, 7, and 8, the shaft 130 B has secured to it between the pillars or standards A⁴ a tappet-cam B¹⁵, (see Fig. 8,) which coöperates with a follower-roll f^x, rotatably mounted on a pin f, extended trans-

versely through a box-like portion or hood F^x of a link F , the hood extending over the tappet and protecting the same from dust and dirt, the sides of the hood being longitudinally slotted, as at f' , Fig. 8, to embrace the shaft B and permit longitudinal movement of the link F by or through the co-operation of the follower-roll with the tappet B^{15} . The link is bifurcated at f^2 to receive between such bifurcated portions or sides a boss f^8 , Fig. 7, on the upper end of a pawl-carrier F' , a pin f^4 pivotally connecting the link and pawl-carrier. The lower end of the latter is provided with a hub f^5 , through which is extended a short shaft F^2 , rotatably mounted in bearings F^3 , secured to or forming part of a cam-bracket F^4 , mounted on the bed of the machine between the pillars A^4 and the raised part A' thereof, as shown in Fig. 1. The hub f^5 is provided with a depending hook f^6 , (see Fig. 7,) to which one end of a strong spring S^3 is attached, the other end of the spring being fixedly secured to a part of the bed, the spring acting to keep the follower f^x in engagement with the tappet-cam B^{15} and to effect the retractive stroke of the pawl-carrier. A toothed disk or ratchet f^7 is secured to the shaft F^2 adjacent the hub f^5 , the hub f^8 of the ratchet being extended to the left, viewing Fig. 7, and into the hub f^5 of the pawl-carrier, forming a bearing for the latter and upon which the pawl-carrier rocks. A pawl f^9 is pivotally mounted at f^{10} on the pawl-carrier to co-operate with the ratchet, the free end of the pawl having projecting laterally therefrom a pin or stud f^{12} , said pin extending over the upper convexed end 75 of a controlling device or detent, shown as a longitudinally-slotted bar f^{13} , embracing the shaft F^2 and having a depending stem f^{14} , adapted to enter a socket f^{15} (see dotted lines, Figs. 7 and 8) in a depending enlargement F^5 of the bracket F^4 . The lower end of the stem f^{14} is reduced in diameter, as at f^{16} , and extends loosely through a hole in the bottom of the socket, a suitable spiral spring, as s^{10} , surrounding such reduced portion in the socket f^{15} between the bottom thereof and the lower end of the stem f^{14} , said spring normally acting to elevate the bar f^{13} and maintain it in the position shown in Figs. 7 and 8 to act through the pin f^{12} to lift the pawl f^9 from engagement with the ratchet. The shaft B is rotated continuously, it will be remembered, and thus the pawl-carrier F' is rocked or swung about the shaft F^2 as a center; but so long as the controlling device is in the position shown in said Figs. 7 and 8 the pin F^{12} will ride over the convex surface 75 and will not engage the ratchet. The bar f^{13} has extended therefrom a lug f^{17} , having a cam-face f^{18} for a purpose to be described, and a suitable spring-controlled detent-pawl f^{19} prevents retrograde movement of the ratchet, the detent-pawl f^{19} being made as a plunger-pawl and controlled by a suitable spring s^{15} . (See dotted lines, Fig. 7.) A circular disk

P, having an elongated hub p^x , is rigidly secured to the shaft F^2 between the slotted bar f^{13} and the right-hand bearing F^3 , viewing 70 Fig. 7, said disk having a reentrant portion or notch p in its periphery and a lateral pin p' projecting from the disk above the notch. The inner face of the disk is cam-shaped to constitute a pattern, the lowest portion thereof being at the point 200 at the top of the notch p , and the high point is located at 300 at the bottom of the notch, the face of the disk gradually rising in an annular direction from 200 to 300. 80

Referring now more particularly to Figs. 1 and 3, the turn-table W has extended laterally therefrom and toward the rear of the machine a rigid arm W^{40} , provided at its extremity with an extension w^{40} of such dimensions that it can readily enter or leave the notch p of the pattern-disk, said notch being in the lateral path of movement of the extension when the work-holder is swung. 85

The rear one of the brackets D^2 , which is 90 the one shown in detail, Fig. 5, has a socket d^{30} therein to receive a coiled spring s^{40} , which surrounds and controls a headed plunger-bolt d^{40} , which is longitudinally movable in the socketted part of the bracket, the head d^{41} of 95 the bolt being in the path of movement of the outer end of the arm W^{40} when swung in the direction of arrow 11, Fig. 1.

Referring to Fig. 1, the arm W^{40} has mounted on its side a stop w^{45} , fulcrumed on a stud w^{46} , and a spring s^{46} is coiled around the stud in a socket in the arm, one end of the spring being fixed and its other end being secured to the stop w^{45} , the winding of the spring being such that normally it maintains a lug w^{47} 100 thereon against a stop-pin w^{48} on the arm. When the operator swings the work-table to present the work to the grinding-surfaces, the extension w^{40} passes through the notch p , and the stop w^{45} engages the lateral pin p' on the 105 disk P at the instant the lower edge of the extension w^{40} has traveled over the beveled face f^{18} of the projection f^{17} on the pawl controller or detent f^{13} and onto the top of said projection, depressing the latter as the stop w^{45} 110 brings up against the pin p' . Any additional manual movement of the work-holder is thereby prevented, and the operator cannot by inadvertence press the work against the grinding-surface. The depression of the 115 detent f^{13} releases the pawl f^9 , and the latter engages the ratchet f^7 , and through the rotation of the ratchet the disk P is turned in the direction of the arrow, Fig. 8, far enough to move the upper edge of the notch 120 p below the top of the extension w^{40} . Consequently when the operator releases the handle W^8 the spring S will act to hold the extension against the pattern or cam-face of the disk P at its low point; but the extension 125 w^{40} will continue to depress the detent f^{13} , so that the pawl and ratchet will remain in co-operation. The continued rotation of the disk P thus effected causes its pattern or cam-sur- 130

face to act upon the extension w^{40} , which then serves as a follower to gradually swing the work-holder in the direction of arrow 11, keeping the work up to the grinding-surface, it being manifest that the pin p' will pass beneath the lower edge of the stop w^{45} just after rotation of the disk P is begun. The movement of the work-holder to operatively position the work is thus made effective to start the movement of the pattern automatically, so that the work-holder is placed under the control of the means for automatically governing its movement during the grinding. The shape or contour of the pattern is such that as the grinding progresses the work will be advanced to the grinding-surface to give to the work the desired shape. Just before the stop w^{45} encounters the pin p' the arm W^{40} engages the plunger-bolt d^{40} , the latter acting to cushion the blow and prevent the stop from sticking with improper force against the pin p' , and as the pattern moves the arm W^{40} during the grinding the spring S^{40} of the plunger-bolt will permit the latter to yield to such movement.

It will be manifest that the action of the pattern will move the stop w^{45} close to the outer face of the disk P as the high part of the pattern is approached and into the path of the pin p' ; but owing to the pivotal mounting of said stop it will be depressed by the pin against the stress of its spring s^{46} until the notch p comes into position opposite the extension w^{40} at the completion of the grinding. Immediately the spring S is free to act to swing the work-holder into the position shown in Fig. 1 and as the arm W^{40} swings oppositely to arrow 11 the extension releases the detent f^{13} and moves out through the notch p . The lifting-spring s^{10} , Figs. 7 and 8, at once elevates the detent, and the pawl and ratchet are disengaged, the pattern-disk P coming to a stop in its original starting position. During the movement of the work-holder, due to the spring S, the work-clamps will be released or opened, as described, and the projections d^4 on the short arms d^2 act to finally stop the work-holder in the position shown in Fig. 1, with the piece of work unclamped and ready to be removed.

The grinders are rotated by means of suitable belts (not shown) cooperating with the pulleys G^x and run from any suitable overhead shaft, and in like manner the front and rear chucks of the work-holder are rotated by belting engaging the pulleys w^{16} , the latter being grooved to prevent the belting from slipping off when the work-holder is swung on its fulcrum W' .

In actual practice the belting driving the chucks will preferably be so arranged as to effect their rotation only while the work is clamped; but that may be accomplished in any convenient manner and is not shown, as it forms no part of my present invention.

By using different patterns the shape to be given the ends of the work will be varied ac-

cordingly, and by reference to Figs. 9 and 10 it will be seen that the square ends of the blank M are by the grinding reduced to tapered or conical extremities $m^1 m^2$, the angle of the side of the cone depending upon the pattern and the adjustment of the working parts.

Not only may the grinders be adjusted toward and from each other, but the work-holder can be adjusted for work of different lengths, and by means of the stops d^5 the clamp-releasing devices can be adjusted correspondingly.

The control of the work is automatically assumed just as soon as the workman swings the work-holder far enough to start the automatic controlling means, and thereafter the control is automatic until the grinding is completed, so that no carelessness, inattention, or lack of skill on the part of the workman can injure the grinders or the work.

I have shown one practical embodiment of my invention without attempting to show or describe the various changes or modifications which may be made therein by those skilled in the art without departing from the spirit and scope of my invention.

Having described my invention, what I claim as new, and desire to secure by Letters Patent, is—

1. In a grinding-machine, a grinding-surface and a work-holder, means to effect their relative movement to place the work in operative position, and independent means to thereupon automatically assume control of and govern the relative movement of said grinding-surface and the work-holder during the completion of the grinding operation.

2. In a grinding-machine, a grinding-surface and a work-holder, manually-operated means to effect their relative movement and place the work-holder in operative position, and means to thereupon automatically assume control of and govern the relative movement of the grinding-surface and work-holder during the completion of the grinding operation.

3. In a grinding-machine, a rotatable grinding-surface and a rotatable work-holder, means to move one relatively to the other to present the work to the grinding-surface, and independent automatic means to thereupon assume control of and govern such relative movement of the parts during the completion of the grinding operation.

4. In a grinding-machine, a rotatable grinding-surface, means to automatically reciprocate it bodily, a work-holder, means to move it to present the work to the grinding-surface, and automatic means to thereupon assume control of and govern subsequent movement of the work-holder during the grinding operation.

5. In a grinding-machine, a rotatable grinding-surface, means to automatically reciprocate it bodily, a rotatable, bodily-movable work-holder, manually-operated means to

move it to present the work to the grinding-surface, and means to automatically assume control of the work-holder after such movement and to control the subsequent bodily movement thereof during the completion of the grinding operation.

6. In a grinding-machine, a rotatable grinding-surface, means to automatically reciprocate it bodily, a work-holder, means to move it to present the work to the grinding-surface, means to thereupon automatically assume control of and govern subsequent movement of the work-holder during the grinding operation, and a device to automatically release the work-holder from the control of said automatic means when a predetermined movement of the work-holder has been effected thereby.

7. In a grinding-machine, a grinding-surface, and a work-holder, means to effect their relative movement to present the work to the grinding-surface, automatic means to thereupon assume control of and govern such relative movement during the grinding operation, and a device to automatically render said latter means inoperative when a predetermined relative movement of the grinding-surface and work-holder has been effected by said automatic means.

8. In a grinding-machine, a rotatable grinding-surface, means to reciprocate it bodily, a work-holder, manually-operated means to move it to present the work to the grinding-surface, automatic means to thereupon assume control of and govern subsequent movement of the work-holder, to give the requisite shape to the work, and a device to automatically release the work-holder from the control of said automatic means when by a predetermined movement of the work-holder the desired grinding has been effected.

9. In a grinding-machine, a rotatable grinding-surface, means to bodily reciprocate the same, a rotatable work-holder bodily movable about a fulcrum at right angles to its axis of rotation, means to move it about such fulcrum to present the work to the grinding-surface, automatic means to thereupon assume control of and govern subsequent bodily movement of the work-holder to complete the grinding, a device to automatically release the work-holder from the control of said automatic means, and a spring to return the work-holder to inoperative position when so released.

10. In a grinding-machine, a rotatable grinder having a flat grinding-surface, means to bodily reciprocate the grinder, a work-holder, manually-operated means to move it in a lateral path to present the work to the grinding-surface at an angle thereto, automatic means to thereupon assume control of the work-holder and change the angle of presentation of the work during grinding, to give the requisite shape to the work, and a device to automatically release the work-holder from such control when a predetermined automatic

movement of the work-holder has been effected.

11. In a grinding-machine, a rotatable grinder having a flat, annular grinding-surface, means to reciprocate the grinder, a rotatable work-holder having its axis of rotation in a plane at right angles to the grinding-surface, a pivot upon which the work-holder is bodily movable, to vary the angle between the intersecting axes of rotation of the grinder and work-holder, means to move the work-holder upon its pivot to present the work to the grinding-surface, and automatic means to thereupon assume control of and govern subsequent bodily movement of the work-holder during the grinding, to advance the work and change the angle of presentation thereof to the grinding-surface, thereby giving the work the requisite shape.

12. In a grinding-machine, a rotatable grinder having a flat, annular grinding-surface, a work-holder to present the work to the grinding-surface, and means to bodily reciprocate the grinder at right angles to its axis of rotation and thereby equalize the wear upon its grinding-surface.

13. In a grinding-machine, a rotatable grinder having a flat grinding-surface, a support therefor, adapted to rock on a fulcrum parallel to the axis of rotation of the grinder, means to rock the support, and a work-holder to present the work to the grinding-surface, the reciprocation of the grinder by or through its rocking support equalizing the wear upon the grinding-surface.

14. In a grinding-machine, a rotatable shaft, a support therefor adapted to rock on a fulcrum parallel to the shaft, a grinder secured to the latter and having a flat, annular grinding-surface, means to rock the support on its fulcrum, a work-holder, and means to move it in a lateral path to present the work to the grinding-surface, the wear upon the latter being equalized by the reciprocation imparted to the grinder by rocking its support.

15. In a grinding-machine, a rotatable grinder having a flat grinding-surface, a support therefor, adapted to rock on a fulcrum parallel to the axis of rotation of the grinder, means to rock the support, a work-holder adapted to be swung in a lateral plane, to present the work to the grinding-surface, a fixed fulcrum on which the work-holder is movable, and means to adjust the grinder-support in the direction of the length of its fulcrum.

16. In a grinding-machine, a rotatable grinding-surface, a work-holder, including means to clamp the work, means to effect relative movement of the grinding-surface and the work-holder, to present the work to the former, and means actuated automatically by or through such relative movement to set the clamping means.

17. In a grinding-machine, a rotatable grinding-surface, a work-holder including a work-clamp, means to effect relative move-

- ment of the grinding-surface and the work-holder, to move the work into and out of position to be ground, and means actuated automatically by or through such relative movement to set the clamping means when the work is presented to the grinding-surface, and to release the clamping means when the work is withdrawn from operative position.
18. In a grinding-machine, a grinding-surface, a work-holder, means to manually effect relative movement of said parts to operatively position the work, means to automatically control the position of the work relative to the grinding-surface during grinding, and a device to automatically place the work-holder under the control of said controlling means when the work is operatively positioned, and to release the work-holder from such control when grinding has been completed.
19. In a grinding-machine, a grinding-surface, a work-holder, means to manually effect relative movement of said parts to operatively position the work, a pattern to control the position of the latter relatively to the grinding-surface during the grinding operation, intermittently-operative means to move the pattern, and a starting device for said means, actuated by manual movement of the work-holder to operatively position the work.
20. In a grinding-machine, a grinding-surface, a work-holder, means to manually effect relative movement of said parts to operatively position the work, a pattern to control the position of the latter relatively to the grinding-surface during the grinding operation, intermittently-operative means to move the pattern, a starting device for said means actuated by operative positioning of the work, and a device to render said means inoperative when a predetermined grinding has been effected.
21. In a grinding-machine, a grinding-surface, a work-holder, means to effect relative movement of said parts to operatively position the work, a rotatable pattern to control the position of the latter relatively to the grinding-surface during grinding, intermittently-operative means to rotate the pattern, a starting device for said means, actuated by or through operative positioning of the work, and means actuated by a predetermined rotation of the pattern to effect the stoppage of the means for rotating it.
22. In a grinding-machine, a rotatable grinding-surface, a work-holder movable in a lateral path to move the work into and out of operative position relatively to the grinding-surface, an intermittently-rotatable pattern to control the position of the work during grinding, said pattern having a notch in its periphery, means bodily movable with the work-holder to pass through the notch and effect the starting of the pattern, the latter acting through said means to control the work-holder during grinding, and a spring to return the latter to inoperative position when rotation of the pattern has brought the notch therein opposite the said means.
23. In a grinding-machine, a rotatable grinding-surface, a work-holder movable in a lateral path to move the work into and out of operative position, relatively to the grinding-surface, an intermittently-rotatable pattern to control the position of the work during grinding, means to rotate the pattern, a device—operated by or through movement of the work-holder to operatively position the work—to effect the rotation of the pattern by said means, the position of the work relatively to the grinding-surface being thereafter controlled by said pattern during grinding, and a stop to limit the movement of the work into operative position and thereby prevent injury of the grinding-surface.
24. In a grinding-machine, a rotatable grinding-surface, a work-holder, means to move it manually to place the work in operative relation with the grinding-surface, an intermittently-rotatable pattern to control the position of the work relatively to the grinding-surface during grinding, means operated by or through such manual movement of the work-holder to effect control thereof by the pattern and start the rotation of the latter, and independent means to automatically withdraw the work from the grinding-surface and effect stoppage of the pattern when the latter has made a predetermined movement.
25. In a grinding-machine, a rotatable grinding-surface, a work-holder, means to move it to operatively position the work relatively to the grinding-surface, a follower movable with the work-holder, a pattern with which the follower coöperates during the grinding, means to actuate the pattern, and a starting device for said means, operated by or through movement of the work-holder, to operatively position the work, such movement also bringing the follower into coöperation with the pattern, the latter thereafter controlling the position of the work with relation to the grinding-surface.
26. In a grinding-machine, a grinding-surface, a work-holder, means to move the latter manually to operatively position the work, means, including a rotatable pattern, to automatically control the movement of the work-holder during grinding, mechanism to rotate the pattern, comprising a ratchet rotatable therewith, a constantly-reciprocating pawl-carrier, and a pawl thereon, and a device to maintain the pawl inoperative, the manually-actuated movement of the work-holder causing said device to release the pawl and permit its coöperation with the ratchet.
27. In a grinding-machine, a grinding-surface, a work-holder, means to move the latter manually to operatively position the work, means, including a rotatable pattern, to automatically control the movement of the work-holder during grinding, a pawl and ratchet to effect rotation of the pattern, a pawl-controller to normally maintain it inoperative, and a dog movable with the work-holder, to retract the pawl-controller when the work is opera-

tively positioned, disengagement of the dog and pawl-controller upon completion of the grinding permitting the latter to disengage the pawl and ratchet.

5 28. In a grinding-machine, a turn-table, a work-holder mounted thereon, including a work-clamp, a spring to set the clamp, and a releasing device to act in opposition to said spring and effect the opening of the clamp, and means to automatically operate the releasing device when the work-holder is in position to receive or discharge the work.

10 29. In a grinding-machine, a turn-table, a work-holder mounted thereon, including a work-clamp, a spring to set the clamp, and a releasing device to act in opposition to said spring and effect the opening of the clamp, said device including a sliding plunger, and means to engage and move the plunger to effect the operation of the releasing device when the work-holder is moved into position to receive or discharge the work.

15 30. In a grinding-machine, a turn-table, a work-holder mounted thereon, including a work-clamp, a spring to set the clamp, and a releasing device to act in opposition to said spring and effect the opening of the clamp, said device including a sliding plunger, and means to engage and move the plunger to effect the operation of the releasing device when the work-holder is moved into position to receive or discharge the work, said means including a spring-controlled, swinging actuator to coöperate with and move the plunger.

20 31. In a grinding-machine, a turn-table, a work-holder mounted thereon, including a work-clamp, a spring to set the clamp, and a releasing device to act in opposition to said spring and effect the opening of the clamp, said device including a sliding plunger, and means to engage and move the plunger to effect the operation of the releasing device when the work-holder is moved into position to receive or discharge the work, said means including a spring-controlled, swinging actuator to coöperate with and move the plunger, and an adjustable stop to engage the actuator and limit the movement imparted thereby to the plunger.

25 32. In a grinding-machine, a work-holder mounted to turn on a vertical pivot, and including rotatable front and rear chucks, a work-clamp in each, and means to automatically close the work-clamps when the work-holder is moved into operative position, and to open said clamps when moved into position to receive or discharge the work.

30 33. In a grinding-machine, a work-holder mounted to turn on a vertical pivot, and including rotatable front and rear chucks, a work-clamp in each, means to move the chucks toward and from each other in accordance with the length of the work, springs to close the clamps, and means to automatically effect the opening thereof by or through movement of the work-holder into position to receive or discharge the work.

34. In a grinding-machine, a work-holder mounted to turn on a vertical pivot, and including rotatable front and rear chucks, a work-clamp in each, means to automatically close the work-clamps when the work-holder is moved into operative position, clamp-opening means to automatically effect the opening of the clamps when the work-holder is in position to receive or discharge the work, and a device to stop the work-holder in such position.

35. In a grinding-machine, two rotatable, oppositely-facing grinding-surfaces having their axes of rotation in parallelism and non-aligned, a work-holder mounted between the grinding-surfaces and adapted to turn bodily on a vertical pivot, means to turn said work-holder to present the opposite ends of the work to the respective grinding-surfaces, and automatic means to thereupon assume control of and govern the movement of the work-holder thereafter during the grinding.

36. In a grinding-machine, two rotatable, oppositely-facing grinding-surfaces having their axes of rotation in parallelism and non-aligned, means to bodily reciprocate the grinding-surfaces with their acting faces in parallelism, a work-holder mounted between the grinding-surfaces and adapted to turn bodily on a vertical pivot, means to turn said work-holder to present the opposite ends of the work to the respective grinding-surfaces, and automatic means to thereupon assume control of and govern the movement of the work-holder thereafter during the grinding.

37. In a grinding-machine, two rotatable, oppositely-facing grinding-surfaces having their axes of rotation in parallelism and non-aligned, means to bodily reciprocate the grinding-surfaces with their acting faces in parallelism, a rotatable work-holder mounted between the grinding-surfaces and adapted to turn bodily on a vertical pivot, manually-operated means to swing the work-holder to present opposite ends of the work to the respective grinding-surfaces, and means to thereupon automatically assume control of and govern the swinging movement of the work-holder during the grinding.

38. In a grinding-machine, two rotatable, oppositely-facing grinding-surfaces having their axes of rotation in parallelism and non-aligned, a work-holder mounted between the grinding-surfaces and adapted to turn bodily on a vertical pivot, means to turn said work-holder to present the opposite ends of the work to the respective grinding-surfaces, means to thereupon automatically assume control of and govern the swinging movement of the work-holder during the grinding, and an adjustable, fixedly-mounted size-gage to prevent swinging movement of the work-holder if the work is overlength.

39. In a grinding-machine, two rotatable, oppositely-facing grinding-surfaces having their axes of rotation in parallelism and non-aligned, means to adjust the grinding-surfaces

toward and from each other, for work of different lengths, a work-holder mounted between the grinding-surfaces and adapted to turn bodily on a vertical pivot, means to turn 5 said work-holder to present the opposite ends of the work to the respective grinding-surfaces, and automatic means to thereupon assume control of and govern the movement of the work-holder thereafter during the grinding.

40. In a grinding-machine, two rotatable, oppositely-facing grinding-surfaces having their axes of rotation in parallelism and non-aligned, a work-holder mounted between the 15 grinding-surfaces and adapted to turn bodily on a vertical pivot, means to turn said work-holder to present the opposite ends of the work to the respective grinding-surfaces, automatic means to thereupon assume control 20 of and govern the movement of the work-holder thereafter during grinding, a rotatable controlling-shaft, connections between it and the grinding-surfaces, to reciprocate them with their acting faces in parallelism, and 25 mechanism driven by said shaft to operate said automatic means.

41. In a grinding-machine, two annular, rotatable grinders having parallel, inwardly-facing, flat grinding-surfaces, the axes of rotation of the grinders being in parallelism 30 and non-aligned, means to continuously reciprocate the grinders with their grinding-surfaces in parallelism, a rotatable work-holder mounted between the grinders to swing on a vertical pivot, means to manually swing the 35 work-holder to present the opposite ends of the work to the respective grinders, a spring to return the work-holder to inoperative position, intermittently-operating means to automatically govern the swinging movement of 40 the work-holder during grinding, actuating mechanism for said means, and a device to automatically effect the actuation of the governing means by said mechanism by or through the operative positioning of the work. 45

In testimony whereof I have signed my name to this specification in the presence of two subscribing witnesses.
